UNITED STATES PATENT OFFICE

1,984,955

INSERTING AND WRAPPING MACHINE

Raymond E. Ackley, Chicago, Ill., assignor to R. R. Donnelley & Sons Co., Chicago, Ill., a corporation of Illinois

Application July 9, 1932, Serial No. 621,718

28 Claims. (Cl. 270—23)

My primary object generally stated is to provide improvements in machines of the general character above referred to, to the end that the machine will be better adapted to perform its functions, and to improve upon various parts and mechanisms of wrapping machines in general and also on combined inserting and wrapping machines.

Certain of my more particular objects are to improve upon the means for delivering the books to a trough through which they are conveyed; to improve the construction of the discharge end of the trough and provide mechanism for effecting the desired delivery of the books therefrom; to provide improvements in the insert-feeding means whereby properly timed delivery of the inserts into the open book will be effected; to improve upon the gripper devices for conveying the wrappers and books through the machine and the mechanism which operates these devices; to provide a novel arrangement of conveyor means for the wrapper and the articles to be wrapped; to provide a novel construction of gripping mechanism for feeding the wrappers and the grouped wrappers and articles in the machine; to provide improvements in book-feeding means whereby fanning of the books will be avoided; to provide improvements generally in the folding means for effecting the wrapping of the articles and more particularly to adapt these means for wrapping books of different thicknesses and also very thin and readily distortable books; to provide in a machine employing gripper-feed mechanism the grippers of which become surrounded by the wrapper before release, for the relative separation of the wrapped books and the grippers to avoid danger of impairment of the wrappers.

Referring to the accompanying drawings:

Figure 1 is a view in side elevation of one end 40 of an inserting and wrapping machine embodying my invention.

Figure 1^a is a similar view of the intermediate portion of the machine; and

Figure 1^b is a similar view of the other end of 45 the machine, these three views taken together constituting a view in side elevation of the entire machine.

Figure 2 is a plan view of the end of the portion of the machine shown in Fig. 1.

Figure 2^a is a plan view of the portion of the machine shown in Fig. 1^a; and

Figure 2^b, a plan view of the portion of the machine shown in Fig. 1^b; Figs. 2, 2^a, and 2^b constituting a plan view of the entire machine.

Figure 1^c is a broken sectional view taken at

the line 1^a on Fig. 1^a and viewed in the direction of the arrow.

Figure 2' is a cross sectional view taken at the irregular line 2' on Fig. 2 and viewed in the direction of the arrow. 5

Figure 3 is an end view of the machine, the machine being viewed from the left-hand end of Fig. 1.

Figure 4 is an enlarged sectional view taken at the line 4—4 on Fig. 1 and viewed in the direction 10 of the arrow.

Figure 5 is an enlarged sectional view taken at the line 5—5 on Fig. 1^a and viewed in the direction of the arrows.

Figure 6 is an enlarged sectional view taken at 15 the line 6—6 on Fig. 1^a and viewed in the direction of the arrows.

Figure 7 is an enlarged cross sectional view taken at the irregular line 7—7 on Fig. 2^b and on the line 7—7 on Fig. 1^b and viewed in the direction 20 of the arrows.

Figure 8 is a fragmentary enlarged plan view of a portion of the mechanism shown in Fig. 2.

Figure 9 is a section taken at the line 9—9 on Fig. 8 and viewed in the direction of the arrows. 25

Figure 10 is a view in front elevation of switch mechanism shown in Fig. 8 and forming a part 30 of the mechanism therein shown.

Figure 11 is a section taken at the line 11—11 on Fig. 9 and viewed in the direction of the 35 arrows.

Figure 12 is a section taken at the line 12—12 on Fig. 1^a and viewed in the direction of the arrows.

Figure 13 is a section taken at the line 13—13 on Fig. 5 and viewed in the direction of the arrow.

Figure 14 is a plan view of the portion of the machine represented in Fig. 15, this view being 40 taken at the line 14—14 on Fig. 1^a.

Figure 15 is a section taken at the irregular line 15—15 on Fig. 14 and viewed in the direction of the arrows.

Figure 16 is a section taken at the line 16—16 45 on Fig. 14 and viewed in the direction of the arrows.

Figure 17 is an enlarged fragmentary view in vertical sectional elevation of the clip-equipped conveyor forming a part of the machine and one 50 of the means provided for opening the clips.

Figure 18 is a view like Fig. 17 and of the structure therein shown illustrating the clip in opened position.

Figure 19 is a section taken at the irregular 55

- line 19—19 on Fig. 17 and viewed in the direction of the arrows.
- Figure 20 is a section taken at the line 20 on Fig. 1 and viewed in the direction of the arrows.
- 5 Figure 21 is a fragmentary plan view viewing the structure in the plane of the line 21 on Fig. 4 and in the direction of the arrows.
- Figure 22 is a broken section taken at the line 22 on Fig. 1^b and viewed in the direction of the arrows.
- 10 Figure 23 is a broken sectional view taken at the irregular line 23—23 on Fig. 22 and viewed in the direction of the arrows.
- Figure 24 is a perspective view of the book and wrapper therefor, this view showing the relative position occupied by these parts upon the feeding of the book to the wrapper.
- 15 Figure 25 is a similar view showing the first folding step in the wrapping of the book.
- 20 Figure 26 is a similar view illustrating a further folding operation.
- Figure 27 is a similar view illustrating the applying of glue to the wrapper preliminary to the final folding operation.
- 25 Figure 28 is a similar view of the book and wrapper illustrating the folding of the wrapper into final position.
- Figure 29 is a similar view illustrating the book and wrapper in final wrapped condition.
- 30 Figure 30 is a fragmentary sectional view taken at the line 30—30 on Fig. 26 and on the line 30 on Fig. 2^a and viewed in the direction of the arrows and showing the means whereby the book and wrapper are folded into the position shown
- 35 in Fig. 27.
- Figure 30^a is a sectional view taken at the line 30—30^a on Fig. 26 and viewed in the direction of the arrows.
- 40 Figure 31 is a plan view of a portion of the machine of the preceding figures modified in such particulars as to cause one edge of the wrapper to be tucked into the space between flatwise opposed folded portions of the book producing a wrapping of the so-called "tuck under" type.
- 45 Figure 32 is a view in side elevation of the portion of the machine of Fig. 31 which operates on the wrapper to produce the "tuck under" positioning thereof above referred to.
- 50 Figure 33 is an enlarged section taken at the line 33—33 on Fig. 31 and viewed in the direction of the arrows.
- 55 Figure 34 is an enlarged section taken at the line 34—34 on Fig. 31 and viewed in the direction of the arrows.
- Figure 35 is an enlarged section taken at the line 35—35 on Fig. 31 and viewed in the direction of the arrows.
- 60 Figure 36 is an enlarged section taken at the line 36—36 on Fig. 31 and viewed in the direction of the arrows.
- Figure 37 is an enlarged section taken at the line 37—37 on Fig. 31 and viewed in the direction of the arrows.
- 65 Figure 38 is an enlarged section taken at the line 38—38 on Fig. 31 and viewed in the direction of the arrows.
- Figure 39 is a vertical sectional view through
- 70 a modification of the portion of the machine shown in 31, for causing one edge of the wrapper to be inserted between the leaves of the book at the free edge of the latter producing a wrapping of the so-called "tuck in" type, the section being
- 75 taken at a line corresponding with the line 33
- on Fig. 31 and viewed in the direction of the arrows.
- Figures 40, 41, 42, 43 and 44 are cross-sectional views of this modified construction, these sections being taken at lines corresponding with the section lines 34, 35, 36, 37 and 38 on Fig. 31 and viewed in the direction of the respective arrows.
- Figures 45 to 50, inclusive, are cross-sectional views of another modification of the portion of the machine shown in Fig. 31 for wrapping the book in double folded condition, these views being taken progressively along the machine at lines corresponding in position in general with the lines at which the sections for Figs. 33 to 38, inclusive, respectively, were taken on Fig. 31.
- Figures 51 to 56, inclusive, are cross-sectional views of still another modification of the portion of the machine shown in Fig. 31 for the wrapping of a book folded upon itself to form three flatwise opposed folds, these views being taken progressively along the machine along lines corresponding in position generally with the lines at which the sections for Figs. 33—38, inclusive, respectively, were taken on Fig. 31.
- Figure 57 is a plan view of a portion of the machine of Figs. 1 to 30, inclusive, modified in such particulars as to adapt the machine for flat wrapping producing a wrapping of the so-called "tuck-in" type.
- Figure 58 is an enlarged broken view in side elevation of the mechanism of Fig. 57 for pressing together the portions of the wrapper at which the glue is applied.
- Figure 59 is an enlarged section taken at the line 59—59 on Fig. 57 and viewed in the direction of the arrows.
- Figure 60 is an enlarged section taken at the line 60—60 on Fig. 57 and viewed in the direction of the arrows.
- Figure 61 is an enlarged section taken at the line 61—61 on Fig. 57 and viewed in the direction of the arrows.
- Figure 62 is a section taken at the line 62—62 on Fig. 57 and viewed in the direction of the arrows.
- Figure 63 is an enlarged section taken at the line 63 on Fig. 57 and viewed in the direction of the arrows.
- Figures 64 to 68, inclusive, are sectional views taken at the different points along a further modified construction of the machine adapting it for the plain flat wrapping of books, the section lines at which the various sections are taken corresponding generally in location with the section lines 33, 34, 36, 37 and 38 on Fig. 31 and viewed in the same direction; and
- Figure 69, a sectional view of a still further modification of the machine adapting it for the flat wrapping of books to produce a wrapping of the fold-under type, the section being taken at a line corresponding generally with the location of line 35—35 on Fig. 31.
- As a preface to the description of the illustrated constructions, it may be stated generally that the machine involves mechanism operating to feed books from a pile thereof to a support upon which the books rest at their back edges and along which they are moved, the pages being spread apart to receive, if desired, inserts, such as sheets or envelopes, to be supplied with the books; the books then being delivered to become flatwise superposed on wrappers in the form of paper sheets which are automatically fed by the machine into position to be associated with the books as stated in the operation of feeding the

books in the machine; and the wrappers with the books superposed thereon thereupon fed to folding and gluing mechanisms which operate to fold the books into the desired condition and the 5 wrappers about the books in which position the wrappers are glued in place.

As will be understood from the following description both the books and the wrappers may be folded into various conditions, typical ones 10 only being illustrated together with the mechanisms by which such different kinds of foldings may be produced.

Referring to the construction of machine illustrated in Figs. 1 to 23, inclusive, the books to be wrapped are located in a hopper 70 supported 15 on the frame 71 of the machine adjacent one end thereof, namely, the left-hand end in Figs. 1 and 2, the bottom of the hopper and represented at 72 reaching short of the front wall 73 of the 20 latter.

Co-operating with the hopper 70 are means for delivering the books represented at 74 one at a time to a book-receiving trough 75 supported on the frame of the machine and extending lengthwise of the latter, this trough being of general 25 V-shape and along which the books are moved, while supported on their back edges, as herein-after described.

The trough 75 (Figs. 3, 4, 5 and 6) is shown 30 as formed of a lower section 76 of general V-shape and upper side-wall-forming sections 77, the sections 77 at the portions thereof of adjacent the hopper 70 being relatively widely divergent and decreasing progressively in divergence toward the right-hand end of the trough into a condition in which they are substantially parallel adjacent the mechanism hereinlater described for turning the books on their side and delivering them to the wrappers as represented in Fig. 6. 35 The lower section 76 terminates short of the wall-forming portions 77 whereby the trough adjacent the book turning mechanism just referred to is open at its bottom except as closed by a movable closure member hereinlater referred to.

Extending downwardly into the trough adjacent the book hopper 70 are upwardly and outwardly curved stationary plates 78 (Fig. 4) which are spaced apart and are disposed in vertical 40 alignment with the bottom of the trough.

The means for delivering the books 74 one by one from the magazine 70 to the trough 75 and between the plates 78 comprise a pair of continuously rotating rollers 79 (Figs. 4, 8 and 9) 45 located directly below the hopper 70 and having peripheral surfaces of any suitable material as for example rubber, these rollers projecting into slots 80 in the upper edge of the adjacent one of the plates 78.

The rollers 79 are secured to a shaft 81 extending lengthwise of the machine and continuously driven in the direction of the arrow in Fig. 4 by a sprocket chain 82 (Fig. 1) engaging a sprocket on the shaft 81 and a sprocket on a shaft 83 extending lengthwise of the machine and constituting the main drive shaft thereof, the shaft 83 being driven through speed-reduction gear mechanism 84 (Fig. 2b) which, in turn, is driven 55 through a sprocket chain 85 by a motor represented at 86.

Co-operating with the feed rollers 79 are pressure-applying rollers 87 (Fig. 4) adapted to bear against the peripheries of the rollers 79, the rollers 87 being rotatably mounted on a frame 88 60 pivoted between its sides at 89 to arms 90 fixed on

a rock shaft 91. A coil spring 92 connected with the frame 88 at its outer edge and with a stationary part of the machine as represented at 93 serves to maintain the rollers 87 in contact with the peripheries of the feed rollers 79. 5

The shaft 91, in the operation of the machine, is rocked back and forth in timed relation to the feeding of the books from the magazine 70 by the means hereinafter described, to cause the rollers 87 to ride upon the upper surfaces of the 10 books as they are delivered to the feed rollers 79 and establish drive of the books to the trough 75 by the feeding action of the rollers 79, the means for thus rocking the shaft 91 comprising a rod 94 (Fig. 20) pivotally connected at its upper end 15 with the shaft 91 at a point eccentric thereof as indicated at 95 the lower end of this rod being connected with a yoke head 96 which straddles a shaft 97 and carries a roller 98 extending into the continuous cam groove 99 in the face of a 20 disk 100 secured to the shaft 97, the shaft 97 being driven from the shaft 81 by a train of gear mechanism represented at 101 (Fig. 1).

Intermittently operating means are provided for drawing the books 74 at their back edge portions downwardly through the opening in the hopper 70 to position them for engagement with the rollers 87 and 79, the means shown for this purpose comprising suction nozzles 102 (Fig. 4) located below the hopper 70 at opposite sides of 25 each of the two rollers 79, respectively, (Fig. 2) and pivotally connected with links 103 and 104 pivoted at their rear ends to a block 105 secured to the bottom of the hopper 70, the nozzles 102 being connected, through a flexible pipe 106, with 30 the suction end of a suction pump represented at 107. The suction nozzles 102 are pivotally connected at 108 with a rod 109 pivoted at 110 to one arm of a bell crank lever 111 rockably mounted on a stationary rod 112. The other arm 35 of the bell crank lever is pivotally connected at 113 with the stem 114 of a yoke head 115 which straddles the shaft 97, the head 115 being provided with a roller 116 which extends into a continuous cam groove 117 formed on the face of a 40 disk 118 rigid on the shaft 97. The suction nozzles 102 in the rotation of the shaft 97, are swung downwardly from the position shown in Fig. 4 drawing with them the forward edge of the book above it, the cam grooves 99 and 117 being so 45 relatively disposed that following the deflecting of the forward edge of the book downwardly into close proximity to the rollers 79, the mechanism controlled by the cam groove 99 rocks the shaft 91 in counterclockwise direction in Fig. 4 thereby 50 causing the rollers 87 to ride upon the upper surface of the book and under the tension of the spring 92 press the book firmly against the peripheries of the rollers 79 thus feeding the book into the space between the plates 78 to become 55 positioned in the trough 75 as shown in Fig. 4.

The line leading from the pump 107 to the nozzles 102 is shown as provided with a valve 107a (Fig. 3) controlled by a reciprocable actuating element 107b bearing under the action of a spring 60 107c against a cam 97a on the shaft 97 and operating to close the nozzles 102 to the pump 107 during the feeding of the book by the rolls 79 and 87.

To assure the dropping of the book into the 65 trough in properly timed relation to the movement of the feed conveyor hereinlater described, the one of the plates 78 adjacent the hopper 70 is provided with a series of holes 119 (Figs. 8 and 9) 70 in communication, through pipes 120 (Fig. 4), 75

with the outlet, pressure side, of the vacuum pump 107 thereby causing the side of the book superposing this plate to be subjected to air pressure which holds the book away from this plate permitting it to fall practically unimpeded by friction between it and the plate.

To avoid accidental drawing down, by the suction nozzles 102, of more than one book I provide, in accordance with common practice, a separator device represented at 121 provided with a lip or "lifter" 122 and pivotally supported at 123 on a head 124 rigid on the shaft 91, the device 121 having a heel portion 125 (Fig. 21) normally held down on the shaft 91 by a coil spring 126 connected with the pivot pin 123 which is rigid with the device 121, and underlapping the shaft 91 at its free end 127. As the rollers 87 move to the right in Fig. 4 when operated as above stated, the lip 122 engages between the lowermost one of the books in the hopper 70 and the one immediately above it and exerts a lifting force on the books above this lip thereby insuring against the delivery of more than one book at a time and facilitating the feeding of the lowermost book, the spring 126 permitting of sufficient yield to the device 121 to prevent damage thereto in case of jamming.

The books delivered to the trough 75 one by one are advanced along the trough by conveyor mechanism comprising an endless chain 128 (Figs. 1, 2^a, 4 and 14) which extends over sprockets 129 and 130 and travels between guides 131 for the upper reach of the chain and guides 132 for the lower reach thereof. The chain 128 is located exterior of the trough 75 and is provided at intervals with horizontally extending fingers 133 projecting laterally therefrom these fingers in their travel along the upper reach of the chain extending transversely through the trough 75, between the lower section 76 thereof and the lower edges of the plates 77 and thus serve to push the books along the trough to the right in Figs. 1 and 2.

The feeder chain 128 is driven from the shaft 97 (driven from the main drive shaft 83 as above described,) through the medium of a bevel gear 134 (Fig. 3) on the left-hand end of this shaft (viewing it in Fig. 1) meshing with a bevel pinion 135 secured to a shaft 136 which carries the sprocket 129, whereby the drive of the conveyor chain 128 is in timed relation to the operation of the book-delivering mechanism above referred to for engaging each book, as it is delivered to the trough, with one of the feeder fingers 133 for advancing the books along the trough.

Means are provided for insuring the spreading of the books as they move along the trough 75 from a position adjacent the hopper 70, these means comprising a member 137 (Figs. 8 and 9) vertically disposed above the book conveyor 128 and in line with the book being conveyed. The member 137 in the particular construction shown is provided as an element of switch mechanism (Fig. 10) controlling the motor 86 which drives the drive shaft 83 and which operates in the event that the book in engaging the member 137 becomes jammed against this member, to cut off the current supply to the motor. To this end the member 137 is connected with a head 138 rigidly secured to a shaft 139 journaled on a stationary part of the machine and equipped at one end with a plate 140 having a camming surface 141 which, in the event of the jamming of one of the books against the member 137 and resulting in counter-clockwise rotation of the shaft 139 in Figs. 9 and

10, moves against a roller 142 carried by the control lever 143 of an electric switch 144 in circuit with the motor 86 and opens the circuit to the motor. The switch 144 would be of the manually resettable type and the electrical hook-up of the machine such, as is common practice in machines relating to the manipulation of books, that after the current to the motor 86 has been interrupted by the operation of the switch 144, the motor can be restarted only by operating the regular motor starting button following the manual resetting of the switch 144.

The books are carried along the trough 75 in the spread condition referred to for the purpose of permitting of the introducing of inserts 74^a (Figs. 2' and 5) into the books. Any suitable mechanism for this purpose may be provided such as for example the mechanism illustrated generally at 145 and of the same construction as the mechanism shown and above described for feeding the books 74 one by one to the trough 75, with the exception of the air-blast provided for insuring the proper descent of the books into the trough, it being understood that the shaft 81 which carries the rollers 79 would also carry the similar rollers for the insert feeding mechanism; that the shaft 112 forming a part of the mechanism which actuates the suction nozzle would also actuate the suction nozzle of the insert-feeding mechanism and that the shaft 91 which actuates the roller mechanism 87 co-operating with the rollers 79 for feeding, also operates the similar roller mechanism of the insert-feeding mechanism.

Extending over the one of the trough sides 77 which is adjacent to the insert-feeding mechanism 145 is a plate 145^a (Fig. 2') supported at its upper, outer, end on a bracket 145^b secured to a stationary part of the machine, this plate extending into the trough 75, in spaced relation to the above referred to trough side 77 and being so positioned that the inserts 74^a fed by the mechanism 145 descend along this plate. Journaled in the brackets 145^b to extend above the plate 145^a and be out of the path of movement of the inserts in discharging to the plate 145^a, is a rock shaft 145^c provided with depending fingers 145^d which, in the full line position shown in Fig. 2', bear at their lower ends against the lower edge of the plate 145^a and form stop means against which the inserts drop, and in the dotted line position therein shown extend out of engagement with the plate 145^a and the insert, permitting the latter to drop into the open book beneath it, the book being maintained in open position in its travel from the book-opening means 137 to a position beyond the insert-feeding mechanism 145, by the plate 145^a and a stationary bar 145^e located in the trough 75 directly opposite this plate and supported, as by brackets 145^f on the trough 75, to extend in spaced relation to the adjacent trough side 77 as shown (Fig. 2').

Mechanism is provided for rocking the shaft 145^c to position the fingers 145^d to arrest the inserts and after delivery thereto to release them for dropping into the books. This mechanism, which is timed in its operation with the conveyor 128, comprising a crank arm 145^g on the shaft 145^c pivoted to the upper end of a link 145^h, the lower end of which is in the form of a yoke 145ⁱ straddling, and slidably crosswise of, the shaft 97, the yoke 145ⁱ carrying a roller 145^j which extends into a continuous cam-groove 145^k formed in the face of a disk 145^l secured to the shaft 97.

The feeder chain 128 operates to move the

books in the trough to the position represented of the book 74 in Fig. 14 from which position the book is further advanced along the trough by feeder mechanism comprising an endless belt 146 trained about pulleys 147 and 148 (Fig. 14) one reach of the belt extending through a horizontal slot 149 (Fig. 16) in the adjacent trough-side 77, and a presser roll 150 extending through an opening in the other trough-side 77 and opposing the belt 146.

The belt 146 is driven by means of a helical gear 152 secured to the lower end of the shaft carrying the pulley 148, this gear meshing with a second helical gear 153 secured to a shaft 154 journaled on a stationary part of the machine. The shaft 154 is driven by a sprocket chain 155 in turn driven by a shaft 156 provided with a gear 157 meshing with a gear 158 on a shaft 159 connected through the medium of bevel gears 160 and 161 with the shaft to which the sprocket 130 is secured.

The roller 150 is provided for the purpose of forcing the book laterally against the feed belt 146 and to this end is mounted on the end of a lever 162 carried by a vertical rock shaft 163 journaled in a stationary part of the machine, a coil spring 164 surrounding a stationary stud 165 and positioned between a stop 166 on this stud and a lug 167 on the lever 162 tending to swing the roller 150 at all times in a direction toward the path of travel of the book. The rock shaft 163 is connected with a horizontal rod 168 provided with a roller 169 which bears at all times, under the action of the spring 164, against the face 170 of a disk 171 secured to the shaft 159 and provided with a cam 172. In the rotation of the disk 170 the cam 172 engages the roller 169 which momentarily swings the roller 150 away from the path of movement of the book 74 to permit the book to freely move along the trough to a position in which it is interposed between the belt 146 and the roller 150 thereby avoiding possible jamming of the forward edge of the book. The feed mechanism just referred to serves to advance the book 74 into engagement with a stop surface 173 (Fig. 14).

The trough 75 from a point adjacent the right-hand end of the feed chain 128 is provided with a movable bottom forming plate 174 which is secured to arms 175 fixed on a shaft 176 journaled in stationary bearings on the machine, the shaft 176 being provided with an arm 177 (Fig. 15) pivotally connected at 178 with a rod 179 provided with a yoke head 180 which straddles the shaft 156 and is provided with a roller 181 opposing the periphery of a cam 182 secured to the shaft 156, the roller 181 being held against the cam by coil springs 188 surrounding the shaft 176 and tending to rotate this shaft in counter-clockwise direction in Figs. 15 and 16.

The mechanism just described is provided for the purpose of rocking the trough bottom 174 into and out of the position shown in Fig. 15 and by dotted lines in Fig. 16 to release the book at the proper time for downward discharge from the trough.

Means are provided for engaging the book to insure the downward discharge thereof upon the downward displacement of the bottom 174, these means comprising rollers 183 shown as three in number to accommodate different lengths of books and rigidly secured to the shaft 154, the peripheries of these rollers preferably formed of friction-producing material, such as rubber, and represented at 184, extending

through vertical slots 185 in the adjacent trough-side 77. Co-operating with the rollers 183 are presser rolls 186 journaled on the upper ends of the arms 175 and so positioned that when the trough bottom 174 is swung to the dotted line position shown in Fig. 16 they will extend through slots in the adjacent trough-side 77 and press the book against the peripheries of the feed rollers 183.

Secured to a stationary part of the machine are inclined fingers 189 the lower ends of which are located in the path of movement of the book in descending through the trough 75 upon displacement of the trough bottom 174 as above described, the book upon engaging at its back edge with the fingers 189 being deflected laterally as represented in Fig. 15 to become superposed upon conveyor means disposed transversely of the machine and which operate to convey the book to superposed position on the wrapper in which the book is to be wrapped and which is delivered to be superposed by the book, by the mechanism hereinafter described.

The machine is so constructed that should a book become so conditioned in its travel in the trough 75 that it would jam in the constricted portion of the latter, the machine will automatically stop. This is provided for by forming, in one of the trough-walls 77 at the portion thereof closely adjacent to its substantially vertical portion, an opening 77^a (Fig. 1^a) and mounting in this opening a plate 77^b supported on a slideable spring-backed bar 77^c forming a part of a switch device 77^d controlling the motor 86. The switch 77^c, which is caused to open the circuit of the motor 86 by the outward movement of the plate 77^b produced by the lateral pressure exerted against it by a distorted book, would be of the manually resettable type and associated with the electrical hook-up of the machine and referred to in connection with the switch 144 to function in connection with said electrical hook-up as above explained of the switch 144.

The rollers 87 and 150, which operate against the sides of the books in the feeding thereof from the hopper and along the trough, respectively, are cross-ribbed at their peripheries, as shown more clearly of the rollers 150 in Fig. 14 whereby fanning of the books which results when smooth surfaced rollers are used, is avoided.

Referring now to the mechanism for feeding the wrappers one by one in flat sheet condition into a position to be superposed by the books, this mechanism comprises a hopper 190 (Fig. 5) for the wrappers represented at 191, this hopper being shown as of the same general construction as the hopper 70 for the books, suction means are provided comprising a nozzle 192 and in communication with any suitable suction producing means and supported as in the case of the suction nozzle 102 for movement toward and away from the stack of sheets 191 to engage and draw the lowermost one into engagement with feeding means. The nozzle 192 is operated as stated by engaging at a roller 193 thereon with the periphery of a cam 194 fixed on a shaft 195 journaled on a stationary part of the machine, and carrying a sprocket 196 engaging a sprocket chain 197 extending over a sprocket 198 on the main drive shaft 83, the flow of air to the nozzle 192 being controlled through the medium of cam mechanism (not shown) on the shaft 195 as above explained of the means for withdrawing the books from the hopper 70.

The sheet feeding mechanism now being de-

scribed also comprises feed rollers 199 secured to the shaft 195 below the hopper 190 and presser rollers 200 mounted on a frame 201 pivoted to arms 202 secured to an oscillating shaft 203 actuated from the shaft 195 by cam mechanism (not shown) as in the case of the presser roller device for the books as above described, the shaft 203 being equipped with a sheet separating device 204 and corresponding with the device 121 of the book feeding mechanism.

10 The parts just described are so constructed and arranged that the wrappers 191 are drawn down one at a time at their forward edges into engagement with the feed rollers 199 and the presser rollers 200 for delivery to cross-conveyor mechanism which will now be described.

15 The cross-conveyor mechanism just referred to comprises a plurality of endless belts 205 (Figs. 1^a, 5 and 12) trained over end pulleys 206 and 207 journaled on the frame of the machine to cause each belt to present an upper reach portion 208 upon which the wrappers 191 are fed from the hopper 190 and by engagement with which the wrappers are delivered against a stop bar 209, the wrappers being guided against lateral movement by guide bars 210 and 211, the bar 210 being shown as adjustable crosswise of the path of travel of the wrappers.

20 The cross conveyor belts 205 at the portions thereof between the rollers 206 and 207 are trained about idler pulleys 212, 213, 214, and 215, and over drive pulleys 216, the pulleys 214 being so mounted as to serve as belt tighteners.

25 The pulleys 216 are driven in the direction of the arrow by a sprocket chain 217 engaging a sprocket 218 on a shaft 219 to which the pulleys 216 are rigidly secured. The sprocket chain 217 also engages a sprocket 220 fixed on a stub shaft 221 journaled on a stationary part of the machine and provided with a sprocket 222 connected by a chain 223 with a sprocket 224 on the main drive shaft 83.

30 Located adjacent to, and below, the stop 209 is 208 of the cross conveyor belts 205 are series of plates 225 the ends thereof adjacent the feed rollers 199 extending beyond the supporting rollers 207 as shown in Fig. 5 to receive and guide the wrappers to the upper reaches of the belts 205, these ends of the plates over which the upper reaches of the belts 205 extend being slotted as represented at 226 to accommodate the belts and rollers 207.

35 The machine also comprises conveyor means for engaging the wrappers 191 delivered by the mechanism just described to the position shown in Fig. 12 at which they engage the stop 209, and convey the wrappers lengthwise of the machine into a position to become superposed each by one of the books 74 and thereafter move the wrapper and the book in the relative positions stated, to mechanism hereinafter described for enclosing the book in the wrapper, a description of the conveyor mechanism just referred to being as follows:

40 Located adjacent to, and below, the stop 209 is an endless chain conveyor element 227 the links of which are formed with plate portions 228 (Fig. 13) which extend close together at the straight portions of the chain and in effect form a bed. The conveyor 227 is supported on sprockets 229 and 230 and is guided at the portions therebetween by guides 231 provided on a stationary part of the machine, the upper reach of the endless conveyor 227 extending beneath and crosswise

45 of the upper reaches 208 of the cross conveyor belts 205 as shown in Fig. 5.

50 The endless conveyor 227 is continuously operated from the drive shaft 83 through the medium of a worm 232 (Figs. 1^b and 2^b) on the shaft 83 meshing with a worm gear 233 on a vertical shaft 234 rotatably mounted on the machine, the shaft 234 being provided at its upper end with a helical gear 235 meshing with a second helical gear 235^a rigid with a shaft 236 journaled on the machine and to which the sprocket 230 is rigidly secured.

55 The endless conveyor 227 is provided at intervals therealong with grippers in the form of clip devices which are adapted to grip the wrappers for moving them with the conveyor to the point where the books are superposed on the wrappers and thereafter clamp both the books and the wrappers to the conveyor for conveying them through the mechanism hereinafter described for folding the wrappers about the books and gluing them in place.

60 The gripper clips referred to each comprise a plate portion 240 (Figs. 17-19, 22 and 23) supported on the conveyor 227 to extend at the upper reach of the conveyor chain above the plates 228 thereof, and be movable toward and away from the latter while maintained substantially parallel therewith. The support for each clip plate 240 comprises a pair of links 241 each pivoted to one of the pivot pins 242 connecting together the links 242^a of the chain and carrying rollers 242^b engaged by the teeth of the sprockets 229 and 230 for driving the chain, the other ends of the links 241 being pivotally connected with the forward end of the gripper clip 240 by a pivot pin 243 carried by the clip.

65 The support for each clip plate 240 also comprises a pair of links 244 and 245 pivoted between their ends on the one of the pivot pins 242 next adjacent to the pivot pin 242 on which the links 241 are pivoted, the links 244 and 245 being disposed substantially parallel to the links 241 and pivotally connected with a pivot pin 246 carried by the plate 240.

70 The support for the plate 240 as described and shown in Figs. 17, 18 and 23 is at the right-hand, or forward, end of the plate 240 whereby its rear end is rendered free to adapt it to clamp downwardly against the wrapper on the conveyor 227, a coil spring 247 being associated with each of the gripper clips referred to for clamping the plates 240 of the clips against the wrappers. As shown in Figs. 17 and 23, the spring 247 is connected at one end with one of the links 242^a of the conveyor 227 as represented at 248 and at its other end with a cross pin 249 connecting together the links 244 and 245.

75 Means are provided for actuating the gripper clips from the position shown by full lines in Fig. 17 and by dotted lines in Fig. 18, to the open position shown by full lines in Fig. 18 in the movement of these gripper clips slightly beyond the wrapper in the delivered position of the latter represented in Fig. 12, to permit of the movement of the wrapper by the upper reach of the conveyor, as hereinafter described, into a position to be clamped by the gripper clip when the latter is swung back to clamping position. The means just referred to comprise a stationary horizontal bar 250 secured to the frame of the machine and on which a coil spring 251 is mounted, one end of this coil spring engaging a stationary stop 252 and the other end thereof, and represented at 253, extending into the path of move-

ment of a roller 254 journaled on the lower end of the link 244. The engagement of the roller 254 with the spring 251 operates to rock the gripper clip to the full line position shown in Fig. 18, the roller 254 riding over the end 253 of the spring and snapping back, under the action of the spring 247 to the full line position shown in Fig. 17. The spring 251 presents an amount of resiliency only sufficient to cushion the shock due to the impact of the roller 254 therewith.

The wrapper is moved into a position to be clamped by the gripper clip against the plate portions 228 of the conveyor 227 by engaging the wrapper with the conveyor by starter means comprising an arm 255 pivotally supported at its upper end as represented at 256 to a stationary part of the machine in inclined position as shown (Figs. 1^a and 13), a coil spring 257 interposed between an extension 258 of the arm 255 and the head 259 on a rod 260 depending from a stationary part of the machine and on which the extension 258 slides, serving to yieldingly swing the arm 255 to vertical position.

The lower end of the arm 255 carries a segment of a wheel 261 provided at a portion of its periphery with short radially projecting stubs 262 preferably of rubber which, under the action of the spring 257, press with a yielding frictional grip on the wrapper beneath them, through a slot 225^a in certain of the plate portions 225 into frictional driving engagement with the conveyor 227. The wheel-segment 261 is continuously driven at the same surface speed as the conveyor 227 through the medium of a sprocket chain 263 engaging a sprocket on the shaft carrying the wheel-segment 261 and a sprocket on a shaft 264 extending crosswise of the machine and journaled in a stationary portion thereof, the shaft 264 being driven through the medium of a helical gear 265 (Fig. 5) meshing with a second helical gear 266 secured to a shaft 267 driven from the main drive shaft 83 through the medium of a sprocket chain 268 engaging a sprocket 269 on the shaft 195 and a sprocket 270 rigid on the shaft 267, the shaft 195 being driven from the shaft 83 as hereinbefore described.

The wrappers 191 are delivered in succession to a position directly above the conveyor 227, as hereinbefore described, when the elastic stubs 262 of the wheel 261 are out of position to engage the wrapper, these stubs engaging the wrapper, in the rotation of the wheel-segment 261 in the direction of the arrow in Fig. 13 and clamping the wrapper to the conveyor 227 for movement of the latter to the right in Fig. 13 in the open position of the gripper clip, whereby when the clip resumes closed position the wrapper will be gripped thereby and move along with the conveyor 227 to the right in Fig. 13.

Referring now to the mechanism for delivering the books in superposed position on the wrappers, this mechanism comprises a horizontal series of endless belts 271 engaging end pulleys 272 and 273 to cause these belts to present upper horizontal reaches 274 extending above a plate 275 stationary on the machine and located above the plane of the movement of the gripper clips on the conveyor 227. The belts 271 are also trained around other pulleys as explained of the belts 205 certain of these pulleys represented at 276 constituting drive pulleys for driving the belts 271 in the direction of the arrows in Figs. 6 and 12, the pulleys 276 being rigid on the shaft 219. The belts 271 are located directly beneath the books as they are delivered from

the vertical toward horizontal position as shown in Figs. 15 and 16 and as above described, whereupon the belts 271 pick up the books in succession and move them under the guidance of bars 277 and 278, against a stop 279 adjustable crosswise of the machine and in the position shown in Fig. 12 stopping the book, which is of smaller area than the wrapper, in such position as shown, that the book extends only part way across the wrapper leaving a portion of the wrapper as represented at 280 (Fig. 12) uncovered. The book is transferred from this cross transfer mechanism to the conveyor 227 for superposed position on the wrapper and for travel therewith, by means of the conveyor 227 to the folding and gluing mechanisms herein-after described, by mechanism of the same construction as that above described for transferring the wrapper from the cross-conveyor to the conveyor 227 and actuating the gripper clips. Detailed description of this mechanism, therefore, does not appear to be necessary, it being sufficient to state that the swinging arm corresponding with the arm 255 of the mechanism hereinbefore described is represented at 281, the wheel-segment rotatable thereon at 282, and carrying the elastic stubs on a portion of its periphery being represented at 283, this wheel-segment being driven from the shaft 267 by a helical gear (not shown) on the shaft 267 engaging a second helical gear 284 on a cross shaft 285 connected by a sprocket chain 286 with the wheel-segment 282; the stop means for throwing the gripper clip to the open position shown at the right-hand end of Fig. 13 and in the form of a coil spring being represented at 287 and of the same construction as stop 251; and the slot in the plate portion 275 through which the wheel-segment 282 presses the wrapper, with the book thereon, against the conveyor 227 into driving engagement therewith at 275^a.

As will be understood, the gripper clip after passing the right-hand edge of the plate 275 in Fig. 13, engages the spring stop 287 thereby swinging the gripper clip to the open position shown at which time the stubs 283 on the wheel-segment 282 engage the book and effect driving engagement between the wrapper and the conveyor 227 moving the book and wrapper to the right in Fig. 13, the gripper clip then closing down against the adjacent edge of the book and clamping the latter and the wrapper to the plate portions 228 of the conveyor 227.

The mechanism for folding the wrappers 191 about the books 74 and for gluing the wrappers in place in the particular construction now being described and involving the folding of the books, comprises a plate 288, as of metal, extending lengthwise of, and directly above, the upper reach of the conveyor chain 227 and above the plane of movement of the wrappers and the books superposed thereon, the plate 288 being supported at its left hand end only (in Fig. 2^a), as at an upwardly and rearwardly turned end 288^a thereof, on the overhanging end of a stationary bracket 288^b, to permit the books and wrappers to pass beneath it and be folded thereover and about this plate as shown in Figs. 26, 27, 28 and 29. The plate 288 is flexible at its free end in a vertical direction, viz., in a direction parallel to the fold, but relatively rigid in a horizontal direction, viz., in a direction normal to the fold and is so positioned, as shown in the figures last referred to, that when the books and the wrappers are folded thereover by the means

hereinafter described and against one edge of this plate, the books will be folded at substantially their center lines as shown.

The folding mechanism also comprises a flare device represented generally at 289 for producing the fold in the book and wrapper as just stated, and located rearwardly beyond the point at which the plate 288 is supported, this device being shown as comprising a block 290 having a flare surface 291 against which the wrapper, with the book superposed thereon, rides and is folded upwardly and inwardly as represented in Fig. 25, this device also comprising a flare plate 292 (Figs. 2a and 26) so shaped as to cause the portions of the book and wrapper folded upwardly and inwardly as stated, to be folded downwardly against the plate 288 as shown in Fig. 26. The plate 292 is vertically adjustable on the block 290 to adapt it for operation on books of different thicknesses, and to this end the block 290 is shown as containing a vertical T-slot 290a in which a rib 292a on a flange 292b of the plate 292 is slidable, the plate 292 being held in adjusted position by T-bolts 292c, the heads of which extend into the T-slot 290a.

To prevent lateral displacement of the book in a direction away from the flare device 289 in the folding operation stated, the machine is provided with a bar 293 extending alongside the strip 288 and held in place by supporting means represented at 294, the face of this bar being grooved as represented at 295 to receive the adjacent edge of the book.

The machine beyond the flare device 289 is provided with a plate 296 which extends along the conveyor 227 and in vertically spaced relation thereto and above the folded over portion of the book and wrapper and serves to hold these parts in the folded position (Fig. 27).

As will be noted from Fig. 27, the wrapper 191 along one edge thereof extends beyond the folded book as represented at 297 and in the final wrapping operation this extending portion is folded to overlie, and adhere to, the opposite edge of the wrapper superposing the upper fold of the book, as shown in Fig. 29, the machine shown comprising means for applying an adhesive, such as glue, to the upper surface of the free edge 297 of the wrapper preliminary to the folding of this edge portion into the position shown in Fig. 29.

These gluing means comprise a frame structure represented at 500 and mounted to slide crosswise of the machine on a pair of stationary horizontal rods 501 secured to a stationary part of the machine, the frame structure 500 having threaded engagement at 502 with a threaded adjusting shaft 503 rotatably mounted in a cross-bar 504 secured to the outer ends of the rods 501, the purpose of the adjustment just referred to being to adapt the gluing mechanism, the other parts of which are hereinafter described, to accommodate varying extensions of the wrapper beyond the book.

These gluing means also comprise a vertically disposed disk 298 located directly beneath the outer margin of the portion 297 of the wrapper to form a support therefor in the application of the glue. The disk 298 is fixed on a sleeve 505 journaled in a bearing portion 506 of the frame structure 500 and splined at 507 to a shaft 299 journaled in the frame of the machine and driven from the shaft 83 through the medium of a sprocket chain 300 engaging a sprocket 302 on a shaft 303 connected with the shaft 299 through

speed-reducing gear mechanism represented generally at 304.

The gluing mechanism further comprises a disk 305 fixed on a shaft 306 journaled in the frame structure 500 of the gluing mechanism and driven from the shaft 299 through the medium of a bevel gear 307 fixed to the sleeve 505, and meshing with a bevel gear 308 fixed on a shaft 309 journaled on the frame structure 500 and having a bevel gear 310 thereon meshing with a bevel gear 311 on the shaft 306. The shaft 306 is disposed in inclined position and the periphery of the disk 305 from which the glue is applied to the upper surface of the wrapper, is chamfered as represented at 312, the glue to be applied to the wrapper being supplied to the peripheral edge of the disk 305 by a circular member 313 secured to the outer end of the shaft 309 and extending at an edge thereof into a glue pot 314 supported by the frame structure 500 and shown as formed with a removable glue-pan 314a, the peripheral edge of the member 313 being chamfered to fit the periphery 312 of the disk 305.

The mounting of the disk 298 and gear 307 on the sleeve 505 splined to the shaft 299 permits the gluing mechanism to be adjusted bodily crosswise of the machine without disturbing the drive connections.

It may be here stated that the machine is shown as provided with other gluing means represented generally at 315 and comprising a disk 316 rigid on the shaft 299 at the side of the conveyor 227 opposite that at which the gluing mechanism comprising the disk 305 is located, the disk 316 extending into a glue pot 317. While the gluing mechanism 315 serves no purpose in connection with the wrapping of the books in accordance with the illustration in Figs. 24-30, it does have utility in connection with the flat wrapping of the books as is hereinafter described.

Located beyond the gluing mechanism, are means for folding the glued edge of the wrapper into the position shown in Figs. 28 and 29, these means comprising a flare device represented at 318 and affording surfaces whereby as the wrapper is moved lengthwise into engagement therewith this glued edge will be folded upwardly and inwardly and thence downwardly into the position shown in Fig. 29, this flare device being of the same general construction as the flare device 289.

Located beyond the flare device 318 are any suitable means for applying downward pressure to the wrapped book to insure the adherence of the free edge of the wrapper to the portion of the wrapper beneath it. The means shown for this purpose and represented generally at 319 and of well known construction comprise an endless chain element 320 located above the conveyor 227 and supported on sprockets journaled on a frame 321 adjustable up and down through the medium of the mechanism represented generally at 322 and supported on the frame of the machine, the lower reach of the endless chain 320 bearing flatwise against the wrapped books as they are fed through the machine by the action of the conveyor mechanism 227.

The chain 320 is driven by means of a sprocket chain 323 engaging a sprocket 324 fixed on the shaft 83 and a sprocket 325 connected with speed-reducing mechanism represented generally at 326 and shown as driving a slow speed shaft 327 having sprocket chain connection 328 with a shaft 329 to which one of the sprockets supporting the presser chain 320 is connected, the presser chain 320 moving in the direction of the arrow in Fig. 1b.

As will be understood, the book and wrapper during the folding and gluing operations, as above stated, are maintained in engagement with the gripper feed mechanism comprising the gripper 5 clips hereinbefore referred to, which requires the release of the gripper clip from the wrapped book, which is effected in the particular construction shown after the wrapped books leave the presser mechanism 319, by providing a cam device 330 on 10 a stationary part of the machine which is engageable by the rollers on the levers 245 of the gripper clip devices as they successively pass beyond the presser mechanism 319, causing these arms to rock and lift the plate portions 240 to 15 relieve the gripping pressure.

As the gripper plate 240 extends into the wrapped book, means are provided for sufficiently retarding the advancing movement of the wrapped book to insure the separation of the gripper plate 240 20 therefrom before the gripper device moves beyond the plane of the upper reach of the conveyor 227, these means comprising an endless chain 331 supported on sprockets 332 and 333 journaled on a head 334 supported on a stationary part of the 25 machine and overhanging the feed conveyor 227, the chain 331 being provided at intervals with outwardly extending fingers 335 arranged in pairs as represented in Fig. 22 and straddling the conveyor chain 227. The chain 331 is driven by a shaft 327 on which the sprocket 333 is fixed, the speed of the shaft 327 being such as to cause the chain to travel at a somewhat slower speed than the conveyor 227 thus retarding the movement of the wrapped books by the conveyor 227 and permitting 30 the gripper clips to move out of the books as stated, the conveyor 227 operating to continue to drive the wrapped books, retarded by the fingers 335, to the point of discharge, as for example to the conveying means represented generally at 336. The conveying means 336 are shown as of the type comprising a plurality of endless belts arranged side by side, one of which is shown at 337, and supported at their opposite ends on aligned 35 pulleys, one of these pulleys, at the forward end of the belts being represented at 338 and carried by a shaft 339 common to all of the pulleys at this end of the conveyor. The shaft 339 is driven by a sprocket chain 340 engaging a sprocket 341 on the shaft 339 and a sprocket fixed on a shaft 342 journaled on the frame of the machine and driven by the shaft 83 through the medium of bevel gears 343 and 344 on the shafts 83 and 343, respectively.

Referring now to the modification of the wrapping and gluing mechanism as illustrated in Figs. 53 31-38 and adapting the machine to fold the book and wrapper as in the case of the construction of the preceding figures except that one edge of the wrapper is tucked under an edge of the folded over portion of the book, this modification involves the provision of the wrapper 192 of somewhat greater width than the wrapper 192 of Figs. 24-30 and the adjustment of certain parts of the machine to cause the book 74 to become so positioned on the wrapper that the latter extends beyond opposite edges of the book to present not only the projecting edge portion 297 but also a projecting edge portion 345 (Fig. 33).

In this construction a flare device represented generally at 346 and of the same general construction as the flare device 289 is supported on the machine to extend into such position (Fig. 24) as to fold the book 74 and the wrapper into the condition shown in this figure, the machine being provided with a stop plate 347 opposing the back edge of the book to prevent the displacement of

the latter in the operation of the flare device 346 and also with a strip 348 over which the book is folded as shown in Fig. 34 and corresponding with the strip 288 of the construction of the preceding figures.

It may be here stated that in this particular construction the strip 348 is supported along one edge on the stop plate 347 which is supported on a plate 349 secured to the frame of the machine, with a narrow plate 350 interposed between the plates 347 and 349 to afford a laterally opening recess 351 to receive the portion 297 of the wrapper.

The machine also comprises a plate 352 secured to a stationary part of the machine and so 15 disposed as shown as to hold the folded book and wrapper at the folded edge of the book in the position to which it is folded by the flare device 346.

Positioned to underlie the folded over edge 20 portion of the book and hold it in spaced relation to the strip 348 beneath it, as shown in Fig. 34, is an edge reinforcing member 353 supported on arms 354 and 355 adjustably secured to a stationary part of the machine, the book 25 being folded over onto this strip 353 by the action of the flare device 346.

Extending lengthwise of the conveyor 227 adjacent the rear end of the plate 353 is a flare device represented generally at 356 provided for 30 engagement by the portion 345 of the wrapper 191 and serving to turn this edge of the wrapper under the strip 353 and thus into the space between the folded over portion of the book and the portion of the book below it (Fig. 35). The 35 flare device 356 which is supported on an arm 357 secured to a stationary part of the machine extends at its pointed forward extremity 358 above the portion 345 of the wrapper and is formed rearwardly thereof with a downwardly 40 and inwardly bent portion 359 which operates as the wrapper moves along it to fold the edge portion 345 of the wrapper into the position shown in Fig. 35, this tucked-under portion of the wrapper remaining in this position after 45 the wrapper has passed beyond the flare device 356.

The flare device 356 is preferably supported on the arm 357 in a manner to permit this device to yield at its right hand end in Fig. 31 50 in a direction away from the wrapper thereby producing a yielding pressure against the wrapper which produces an ironing effect on the wrapper causing it to be smoothly deflected into tucked-under condition. To this end the flare 55 device 356 is shown as rigidly secured to the lower end of a shaft 356^a rotatable in an opening in the arm 357 and associated with a torsion spring 356^b surrounding the shaft 356^a, this spring being connected at one end with the 60 arm 357 and at its other end with a tension head 356^c rotatably adjustable on the upper end of the shaft 356^a for varying the tension of the spring and held in adjustable position by a cross-pin 356^d on the shaft 356^a and engaging 65 notches 356^e in the head 356^c, the spring tending to resist clockwise rotation of the shaft 356^a and the flare device 356.

The partially wrapped book thence passes to the gluing mechanism above described and comprising the gluing disk 305 and wrapper-supporting disk 298, which applies glue to the upper surface of the edge portion 297 of the wrapper.

Beyond the gluing mechanism is a flare device 359 of the same general construction as the flare 75

device 318 and which operates to turn the edge portion 297 upwardly and thence downwardly on the folded wrapper to the position represented in Fig. 37.

5 After passing the flare device 359 the wrapped book is passed beneath the presser mechanism 319.

The modification of the machine shown in Figs. 39 to 44, inclusive, is the same as that shown in Figs. 31 to 38, inclusive, except that provision is made for tucking in the edge portion 35 of the wrapper between the leaves of the folded over portion of the book instead of tucking it under this folded over portion. To 15 this end the machine is of the same construction as that shown in Figs. 31-38, inclusive, except that instead of folding the edge of the book and the adjacent edge of the wrapper onto a strip, namely, the strip 353 in Fig. 34, the folded over portion of the book and the portion of the wrapper above it fold over flat onto the plate 348 and as the partially wrapped book is advanced by the feed conveyor 227 the folded over portion of the book engages between its ends 20 with the forward edge of a strip 360 corresponding with, and supported as in the case of, the strip 353 but located at a position farther along on the machine than the strip 353 to properly position it for splitting the book as stated.

30 Referring now to the modification of the wrapping and gluing mechanism as illustrated in Figs. 45 to 50, inclusive, and adapting the machine for the wrapping of the book in double folded condition, this modification involves the provision of the wrapper 192 of less width than the book and the adjustment of certain parts of the machine for delivering the books to the wrappers, for causing the book 74 to become positioned on the wrapper as shown in Fig. 45.

40 In this construction the opposite longitudinal edges of the wrapper enter guide grooves 361 and 362 provided on a stationary part of the machine at opposite sides of the conveyor 227, the book extending between guide surfaces 363 and 364 likewise on a stationary part of the machine.

The machine also comprises a strip 365 supported along one edge on a stationary part of the machine and opposite this strip a flare device 366 of the same general construction as the flare device 359 which extends into the path of movement of the edge portion of the book at the right-hand side of Fig. 45 and operates to swing this edge portion upwardly and inwardly and thence downwardly over and upon the strip 365 as shown 55 in Fig. 46.

Beyond the flare device 366 and at the opposite side of the conveyor 227 is another flare device 367 of the same general construction as the flare device 289 which is engaged by the adjacent edge of the 60 wrapper (the wrapper having left the groove 362) and which operates to swing this edge of the wrapper, together with the portions of the books superposing it upwardly and inwardly and thence downwardly to the position shown in Fig. 47 thereby producing a double fold of the book, there being provided opposite the flare device 367, a plate 368 supported at its outer longitudinal edge on a stationary part of the machine and over the free edge portion of which the parts of the wrapper and book which are deflected by the flare device 367 as above stated, are folded as shown in Fig. 47.

Beyond the flare device 367 is the gluing mechanism comprising the disks 298 and 305 as above stated which serves to apply glue to the upper 70 face of the projecting edge portion of the wrapper

as shown in Fig. 48, this edge portion having left the groove 361; and beyond the gluing mechanism referred to is another flare device 369 of the same general construction as the flare device 359 which operates to swing the glued edge of the wrapper upwardly and inwardly to the position shown in Fig. 49 in which it laps the opposite edge of the wrapper as shown. The book and wrapper folded into the condition shown in Fig. 47 is maintained in this condition in traveling 1 through the machine, by a plate 370 supported at a longitudinal edge thereof on a stationary part of the machine and overhanging the partially wrapped book as shown in Figs. 48 and 49.

After passing the flare device 369 the wrapped 1 book passes to the presser device 319 as for the purpose hereinbefore described.

The parts 365 and 368 serve as means for definitely defining the lines along which the book is folded in the successive folding operations above 20 described.

In the modification of the machine shown in Figs. 51 to 56, inclusive, adapting the machine for the wrapping of a book folded upon itself to form three flatwise opposed folds, the opposite edges 21 of the book extend into longitudinal grooves 371 and 372 on a stationary part of the machine and the right-hand edge of the wrapper in Fig. 51 extends into a groove 373.

Supported at its front end, as in the case of 30 the strip 288, is a strip 374 over which the edge of the book at the right-hand side of Fig. 51 is folded by engagement with a flare device 375 of the same general construction as the flare device 318.

Beyond the flare device 375 and at the opposite 35 side of the conveyor 227 is another flare device 376 of the same general construction as the flare device 289 and which operates to fold the edge of the book at the left-hand side of Fig. 52, together with the edge of the wrapper sheet below 40 it into superposed position on the edge of the book folded by the flare device 375, as shown in Fig. 53.

Beyond the flare device 375 is the gluing mechanism comprising the disks 298 and 305 45 which operates to apply glue to the upper surface of the edge of the wrapper at the right-hand side of Figs. 51-54 which leaves the groove 373 before engaging with the gluing mechanism.

Beyond the gluing mechanism referred to is a 50 flare device 377 of the same general construction as the flare device 318 and which operates as the wrapper moves along it to fold the glued edge of the wrapper into the position shown in Fig. 55. The folded, partially wrapped, book 55 (Fig. 53) is held in this condition in its movement through the machine to the presser mechanism 319, by a plate 378 supported along one edge on a stationary part of the machine and overhanging the folded book as shown in Figs. 60 54 and 55.

Referring now to the modification of machine shown in Figs. 57 to 63, inclusive, and adapting the machine for the flat wrapping of books, the machine is shown as provided with a curved bar 65 379 disposed in the path of movement of the right-hand edge of the wrapper in Fig. 59 and which operates to swing the wrapper upwardly and inwardly toward the book into substantially vertical position. Adjacent this deflector bar 70 379 is a flare device 380 with which the edge of the wrapper deflected by the bar 379, as stated, engages and by which this edge of the wrapper is swung around the adjacent longitudinal edge of a strip 380a corresponding with the 75

strip 288 and supported as described of the latter and downwardly to the position shown in Fig. 60 in which its outer edge portion becomes superposed on a plate 381.

5 It may be here stated that the forward edge of the plate 381 is so positioned that as the book moves along the machine this plate enters between certain of the leaves of the book and opens the book as represented in Fig. 60.

10 In this construction the edge of the wrapper extending beyond the book at the left-hand side of Fig. 59 is tucked in between the leaves of the book at the opened up portion thereof and to accomplish this the machine is provided with a 15 flare device 382 of the same general construction as the flare device 289 which turns this edge portion of the wrapper around the edge of a strip 382^a corresponding with the strip 288 and into the position as shown in Fig. 60 in which it 20 extends into the space provided by splitting the leaves as stated. As the book thus partially wrapped continues its movement along the machine it passes the rear ends of the parts 31 and 382^a and the flare device 382, whereupon the 25 leaves of the book, deflected upwardly by the plate 381, and the overlying portion of the wrapper sheet assume the position shown in Fig. 61.

The partially wrapped book as shown in Fig. 61 thence passes, in the movement of the conveyor 227, to means for applying glue as indicated at 383 to the underside of the wrapper adjacent the left-hand edge thereof in Fig. 61, for adhering thereto the edge of the wrapper extending to the left beyond the book in this 35 figure, this edge of the wrapper being folded downwardly around the adjacent edge of the book and a strip 384^a, corresponding with the strip 288, and into underlapping position relative to the glue on the wrapper, by the movement of this edge of the wrapper against a flare device 384 shown as supported on a laterally disposed arm 385 carried by a stationary part of the machine.

The gluing means for applying glue to the 40 wrapper as stated comprise the glue-applying disk 315 of Fig. 7, the gluing mechanism comprising the gluing disk 305 not functioning in this particular modified construction.

As the glued joint of the wrapper is located 45 to one side of the presser mechanism 319, special means are provided as shown for applying squeezing pressure along this joint, a description of the means shown for this purpose being as follows:

50 Journaled on a stationary bracket 386 on the machine is a shaft 387 provided at one end with a gear 388 and at its opposite end with a sprocket 389, this sprocket extending upwardly into a position to be driven at its teeth by the pins 55 which connect the links of the feed conveyor 227. The gear 388 meshes with a pinion 390 journaled on the bracket 386 and meshing with a pinion 391 also journaled on the bracket 386 and connected with a roller 392 located below the 60 wrapped book at its glued edge (Fig. 63).

Pivoted at 393 on the bracket 386 is an arm 394 carrying a roller 395 extending directly above the roller 392 and adapted to bear against the upper surface of the wrapped book, the roller 65 70 75 78 80 85 90 95 98 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 torted under the force exerted in the folding operations were such strips omitted. However, it will be understood that where the books present sufficient inherent stiffness to resist such force, 5 these strips may be omitted.

While I have illustrated and described certain constructions embodying my invention, I do not wish to be understood as intending to limit it thereto as the invention may be embodied in 10 other forms of construction and those illustrated and described variously modified and altered without departing from the spirit of my invention.

What I claim as new, and desire to secure by 15 Letters Patent, is:

1. In a wrapping machine, the combination of a support along which material comprising the article to be wrapped and a wrapper therefor is moved, and a flare device comprising two sections, the first of said sections being adapted to 20 fold a portion of the material to a position substantially at right angles to the support, and the second section being adapted to further fold said portion of the material to a position overlying the support and substantially parallel thereto, 25 said second section being adjustably fastened to the first section in such manner that it may be adjusted toward and away from said support to adapt the flare-device for the wrapping of articles of different thicknesses.

2. In an article-wrapping machine, the combination of a conveyor, a support for an object comprising the wrapper or the article to be wrapped located above said conveyor and means 30 for initially moving the object from said support for movement with said conveyor operative to press the object while on said support into engagement with said conveyor for movement with the latter.

3. In an article-wrapping machine, the combination of a conveyor, a support for an object comprising the wrapper or the article to be wrapped located above said conveyor and means 35 initially moving the object from said support for movement with said conveyor operative to press the article while on said support into engagement with said conveyor for movement with the latter comprising a rotary device for engaging said object.

4. In an article-wrapping machine, the combination of a conveyor, a support for an object comprising the wrapper or the article to be wrapped located above said conveyor and means 40 operative to press the object while on said support into engagement with said conveyor for movement with the latter comprising a wheel for engaging said object and means for rotating said wheel in the direction of movement of said conveyor.

5. In an article-wrapping machine, the combination of a conveyor, a support for an object comprising the wrapper or the article to be wrapped located above said conveyor and means 45 operative to press the object while on said support into engagement with said conveyor for movement with the latter comprising a wheel for engaging said object and means for rotating said wheel in the direction of movement of said conveyor and at substantially the same speed as the latter.

6. In an article-wrapping machine, the combination of a conveyor, a support for an object comprising the wrapper or the article to be wrapped located above said conveyor and means 50 operative to press the object while on said sup-

port into engagement with said conveyor for movement with the latter comprising a wheel having a segmental peripheral portion at which it engages the object.

7. In an article-wrapping machine, the combination of a conveyor, a support for an object comprising the wrapper or the article to be wrapped located above said conveyor and means operative to press the object while on said support into engagement with said conveyor for 10 movement with the latter comprising a wheel having a segmental peripheral portion at which it engages the object and means for rotating said wheel in timed relation to the movement of the conveyor.

8. In an article-wrapping machine, the combination of a conveyor having a gripper jaw to engage an object fed to said conveyor, a support for an object comprising the wrapper or the article to be wrapped located above said conveyor, 20 means operative to press the object while on said support into engagement with said conveyor to the rear of said gripper jaw for movement with said conveyor, and means operative to clamp said jaw against the article on the conveyor.

9. In an article-wrapping machine, the combination of a conveyor having a gripper jaw to engage an object fed to said conveyor, a support for an object comprising the wrapper or the article to be wrapped located above said conveyor, 30 means operative to press the object while on said support into engagement with said conveyor for movement with the conveyor, means for moving said gripper jaw forwardly on said conveyor adjacent said first-named means and means for moving said gripper jaw rearwardly on said conveyor for engaging the object on the conveyor.

10. In a machine of the character set forth, the combination of a conveyor, a gripper thereon, means for feeding a wrapper to said conveyor, 40 means for feeding to said wrapper an article to be wrapped, and gripper operating mechanism operating to cause the gripper to first grip the wrapper, release therefrom and, after delivery of the article to the wrapper, engage the article 45 and grip the latter and the wrapper to said conveyor.

11. In a machine of the character set forth, the combination of a conveyor, a gripper thereon, means for feeding a wrapper to said conveyor, 50 means for feeding to said wrapper an article to be wrapped, and gripper operating mechanism comprising means to first grip the wrapper, means for releasing said gripper from the wrapper and means for engaging said jaw with the article 55 after delivery to the wrapper and gripping the article and wrapper to said conveyor.

12. In a machine of the character set forth, the combination of a conveyor, a gripper thereon, a wrapper support above said conveyor, 60 means for delivering the wrapper from said support to said conveyor, a second support above said conveyor for the article to be wrapped, means for delivering the article from said second support to the wrapper, and gripper operating mechanism operating to cause the gripper to first grip the wrapper, release therefrom and after delivery of the article to the wrapper engage the article and grip the latter and the wrapper to said conveyor.

13. In a wrapping machine, the combination of a conveyor for the wrapper and the article to be wrapped, a gripper on the conveyor for gripping the article and wrapper for movement with the conveyor and which extends between portions 75

of the wrapper, means for releasing clamping engagement of said gripper with the article and wrapper, and means for retarding movement of the article and wrapper relative to the conveyor 5 to permit the gripper to move out of the wrapper.

14. In a wrapping machine, the combination of a conveyor for the wrapper and the article to be wrapped, a gripper on the conveyor for gripping the article and wrapper for movement with 10 the conveyor and which extends between portions of the wrapper, means for releasing clamping engagement of said gripper with the article and wrapper, and means for retarding movement of the article and wrapper relative to the conveyor 15 to permit the gripper to move out of the wrapper comprising a member supported to engage the wrapper and article and means driving said member in the same direction as said conveyor but at a speed less than that of said conveyor.

15. In a wrapping machine, the combination of a conveyor for the wrapper and the article to be wrapped, a gripper on the conveyor for gripping the article and wrapper for movement with 25 the conveyor and which extends between portions of the wrapper, means for releasing clamping engagement of said gripper with the article and wrapper, and means for retarding movement of the article and wrapper relative to the conveyor 30 to permit the gripper to move out of the wrapper comprising an endless traveling member, a projection on said member and adapted to engage the article and wrapper, and means for driving said member in the same direction as said conveyor but at a speed less than that of said conveyor.

16. In a wrapping machine, the combination of a conveyor for the wrapper and the article to be wrapped, a gripper on the conveyor for gripping the article and wrapper for movement with 40 the conveyor and which extends between portions of the wrapper, means for releasing clamping engagement of said gripper with the article and wrapper, and means for retarding movement of the article and wrapper relative to the conveyor 45 to permit the gripper to move out of the wrapper comprising an endless traveling member, a yoke on said member adapted to straddle said gripper and engage the article and wrapper, and means 50 for driving said member in the same direction as said conveyor but at a speed less than that of said conveyor.

17. In a book-wrapping machine, the combination of a conveyor for the wrapper and the book to be wrapped, folding means for wrapping the book and comprising a member adapted to fold an edge of the wrapper between certain portions of the book, and a reinforcing member about which the fold adjacent said edge is made.

18. In a machine of the character set forth, the combination of a conveyor, wrapper-feeding means, a second conveyor extending crosswise of, and substantially parallel with, said first-named conveyor for moving the wrappers in succession from said wrapper-feeding means to a position vertically displaced from said first-named conveyor, means for delivering the wrappers from said second conveyor to said first-named conveyor, book-feeding means, a third conveyor extending crosswise of, and substantially parallel with, said first-named conveyor for moving the books in succession to a position vertically displaced from said first-named conveyor and the wrappers thereon, and means for delivering the books from said third conveyor into superposed

position on the wrappers on said first-named conveyor.

19. In a wrapping machine, the combination of a conveyor for the wrapper and the article to be wrapped, folding means for wrapping the article and a reinforcing member about which the fold is made, said reinforcing member being located adjacent an edge to be wrapped and flexible in a direction parallel to the fold but relatively rigid in a direction normal to the fold.

20. In a wrapping machine, folding means for wrapping an article and a reinforcing member about which the fold is made, said reinforcing member being located adjacent an edge to be wrapped and flexible in a direction parallel to 15 the fold but relatively rigid in a direction normal to the fold.

21. In an article-wrapping machine, the combination of a conveyor, a support for an object comprising the wrapper or the article to be 20 wrapped located above said conveyor, means for feeding the object crosswise of said conveyor to said support, and means operative to press the object while on said support into engagement with said conveyor for movement with the latter 25 comprising a wheel having a segmental peripheral portion at which it engages the object.

22. In an article-wrapping machine, the combination of a conveyor, a support for an object comprising the wrapper or the article to be 30 wrapped located above said conveyor, means for feeding the object crosswise of said conveyor to said support, means operative to press the object while on said support into engagement with said conveyor for movement with the latter comprising 35 a wheel having a segmental peripheral portion at which it engages the object, and means for rotating said wheel in timed relation to the movement of the conveyor.

23. In an article-wrapping machine, the combination of a conveyor, a gripper jaw on said conveyor for engaging an object conveyed to said conveyor, a support for an object comprising the wrapper or the article to be wrapped, located 40 above said conveyor, means for feeding the object crosswise of said conveyor to said support, means operative to press the object while on said support into engagement with said conveyor to the rear of said gripper jaw for movement with said conveyor, and means operative to clamp said 45 jaw against the object on the conveyor.

24. In an article-wrapping machine, the combination of a conveyor, a gripper jaw on said conveyor for engaging an object conveyed to said conveyor, a support for an object comprising the 55 wrapper or the article to be wrapped, located above said conveyor, means for feeding the object crosswise of said conveyor to said support, means operative to press the object while on said support into engagement with said conveyor for movement with the conveyor, means for moving said gripper jaw forwardly on said conveyor adjacent said first-named means, and means for moving said gripper jaw rearwardly on said conveyor for engaging the object on the conveyor.

25. In an article-wrapping machine, the combination of a conveyor, a gripper jaw on said conveyor for engaging an object fed to said conveyor, a support for an object comprising the wrapper or the article to be wrapped located 60 above said conveyor, means for initially moving the object from said support for movement with said conveyor operative to press the object while on said support into engagement with said conveyor to the rear of said gripper jaw for move- 65 70 75

- ment with said conveyor, and means operative to clamp said jaw against the object on the conveyor.
26. In an article-wrapping machine, the combination of a conveyor, a gripper jaw on said conveyor for engaging an object fed to said conveyor, a support for an object comprising the wrapper or the article to be wrapped located above said conveyor, means for initially moving the object from said support for movement with said conveyor operative to press the object while on said support into engagement with said conveyor for movement with the conveyor, means for moving said gripper jaw forwardly on said conveyor adjacent said first-named means, and means for moving said gripper jaw rearwardly on said conveyor for engaging the object on the conveyor.
27. In a wrapping machine the combination of a conveyor for the wrapper and the article to be wrapped, folding means for wrapping the article and a blade contacting a free edge of the article about which a fold is to be made adapted to reinforce and prevent the crumpling of said edge while the wrapper is being folded around it.
28. In a machine of the character set forth, the combination of a conveyor, wrapper-feeding means, a second conveyor a portion of the circuit of which extends across, above and separated from the upper run of said first conveyor, for moving the wrappers in succession from said wrapper-feeding means to a position overlying 10 said first-named conveyor, means for delivering the wrappers from said second conveyor to said first-named conveyor, book feeding means, a third conveyor a portion of the circuit of which extends across, above and separated from, the upper run 15 of said first-named conveyor, for moving the books in succession to a position overlying said first-named conveyor and the wrappers thereon, and means for delivering the books from said third conveyor into superposed position on the 20 wrapper on said first-named conveyor.

RAYMOND E. ACKLEY.
